United States Patent Office

Des. 179,141
Patented Nov. 6, 1956

179,141

DRAFTING DEVICE

Byron D. MacPherson, Seattle, Wash.

Application January 21, 1955, Serial No. 34,114

Term of patent 3½ years

(Cl. D52—1)

Figure 1 is a top plan view of a drafting device, showing my new design.

Figure 2 is a side elevation.

Figure 3 is an end elevation.

Figure 4 is a view of the underside, partly broken away.

Figure 5 is a sectional view taken substantially on the lines 5—5 as shown in Figure 1.

I claim:

The ornamental design for a drafting device, as shown.
